SPRING-LOADED COVER MECHANISM FOR PYROPHORIC LIGHTERS

Erich Körner, Fichtnergasse 14, Vienna XIII, Austria

Filed Jan. 31, 1961, Ser. No. 66,229

Claims priority, application Austria Feb. 8, 1960

7 Claims. (Cl. 67—7.1)

This invention relates to a spring-loaded cover mechanism for pyrophoric lighters, which mechanism is of special advantage in connection with liquid-fueled lighters, the fuel tank of which contains only a liquid charge, in the absence of wadding or the like. In the present connection the term "spring-loaded cover mechanism" is directed to a cover arrangement in which a spring-loaded cover, which normally covers the flame station, flies open when a lock has been released and by doing so rotates the friction wheel whereby the igniting spark is struck out of the pyrophoric flint. Closing of this cover usually causes the straining of a spring to store the power required for opening the cover in the next igniting operation.

Such spring-loaded covers have the disadvantage that the spring which opens the spring-loaded cover is held almost permanently in a strained condition, whereby the life of this spring is greatly reduced.

Other lighters are known, in which the movement of the cover to drive the friction wheel is produced by pressure exerted on the cover by the thumb of the hand which holds the lighter. There are also lighters in which this finger pressure is transmitted to the cover by a transmitting mechanism. Whereas these lighters are widely used, they have a disadvantage which renders their use as liquid-filled lighters objectionable: Since the cover is not firmly urged against its seat, the cover may be unintentionally lifted. When such lifting takes place while the container is not in a vertical position, fuel will flow out of the container. The use of a stronger spring to urge the cover against its seat in order to render an unintended opening more difficult is possible only with great restriction because the force of this spring must be overcome when sparks are to be produced. Lighters which require an extremely long finger pressure for actuation are unsatisfactory.

A spring-loaded cover mechanism for pyrophoric lighters has been proposed, in which a motion-transmitting storage spring provided between the spring-loaded cover and a finger-operated straining member will not move the spring-loaded cover in the opening sense until the straining member has been displaced to impart a predetermined stress to the spring while the spring-loaded cover is closed and until the spring-loaded cover has been released by a locking means holding the cover in its closed position. Whereas this design affords some protection against an unintended lifting of the cover, the latter is also held closed by a fairly strong spring and it is obvious that the reaction force of this spring must become effective at some time during the straining of the spring. This force must be overcome by the finger of the hand which operates the lighter and renders the manipulation of the lighter more difficult.

A spring-loaded cover mechanism of the type mentioned last hereinbefore is characterized according to the invention in that the locking means comprise a toggle joint, which when the spring-loaded cover is closed assumes a straightened position in which the toggle joint precludes a movement of the spring-loaded cover and from which this joint is moved to an angle position permitting of a relaxation of the storage spring to open the spring-loaded cover at the end of each movement whereby the cover loading spring is strained, which consists of a cover loading spring in a manner known per se.

2

The accompanying diagrammatic drawings serve to explain this feature and other features of the invention and illustrate by way of example an embodiment of the present spring-loaded cover mechanism.

5 FIG. 1 is a sectional view taken on line I—I of FIG.

2.

FIG. 2 is a horizontal sectional view taken on line II—II of FIG. 1; and

10 FIG. 3. shows the upper portion of the lighter of the invention in side elevation.

FIG. 1 shows the spring-loaded cover 1, which is fastened on a shaft 2 journaled in the side walls 19 of the lighter housing. Rotation of the cover drives the friction wheel 3 which is fixedly fastened to the shaft 2. For

15 the sake of clarity, the wheel 3 is shown in phantom view in FIG. 1. Thus, sparks are struck out of the flint 4 when the cover is being opened. The spring-loaded cover accommodates the wick cap, which is not shown, as it is not required for the understanding of the invention, and which seals the flame station 11 when the lighter

20 is closed. 5 is the straining member, which consists here of a segment which is rotatable on the shaft 10 and is knurled for a reliable engagement by the thumb of the actuating hand. The storage spring or cover loading

25 spring 7 surrounds a bar 6 and is guided by the same. At one end, 6a, the bar 6 is pivoted to the spring-loaded cover 1 whereas the other end 6b of the bar is slidably mounted in a pivoted part 8, which is rotatably connected to the straining wheel 5. This pivoted part 8

30 forms one abutment of the spring, and a disc 9 or the like firmly connected to part 6 forms the other abutment of the spring 7.

The cover 1 is locked in its closed position by the toggle joint 15, 16 when the same is straightened. This is theoretically sufficient. For reasons of manufacturing practice the toggle joint will be moved somewhat beyond the straightened position to ensure that it will be held in this position by the engagement of one of the levers or rods 15 with a stop 13. One end of the toggle joint

40 is connected at 17 to the spring-loaded cover 1. The other end is connected at 18 to the outside wall or

housing 19 of the lighter. The joint 20 which connects respective end portions of the rods 15, 16 is movable. An extension 16a of the lever 16 extends into the path

45 of movement of an actuating pin 21, which is firmly connected to the straining member 5. The mode of operation is as follows:

When the straining member 5 is strained by a rotation in the direction of arrow B, the spring 7 will be strained 50 or stressed whereas the cover 1 will remain in its closed position because the toggle joint 15, 16 remaining in its straightened position will prevent a rotation of the cover about the shaft 2. Only when the actuating pin 21 strikes the extension 16a of the lever 16 will the latter be moved out of its position of rest through the theoretically perfectly straightened position and be angled; from this time the spring 7, having been strained in the meantime as a result of the rotation of 5, can relax to exert a strong 55 opening impulse to the spring-loaded cover 1. At the end of this movement the toggle joint has reached the position shown by broken lines. A return spring 14, which may be very weak and which has been strained during the rotation of the member 5, will return the entire system to its initial position as soon as the actuating member 5 is released. The ends of the spring 14 engage

60 respective openings in the actuating member 5 and in a stud 12 fixed on the side wall 19.

A small spring 22, which is firmly connected to the cover 1 by a pin 24', tends to hold the lever 15 in the 65 straightened position and ensures that the toggle joint 15, 16 will assume its correct position of rest, in which it is safely held, the lever 15 engaging the stop 13. The

70

return movement of the mechanism to the initial position is effected while the spring 7 is relaxed. This spring may remain practically free of stress when the lighter is not used so that this spring has a long life.

FIG. 2 shows a fragmentary plan view of the mechanism illustrated in FIG. 1. The spring member 6, 7 is centrally disposed whereas the toggle joints 15, 16 are disposed near the sides 19 of the lighter housing. As a result, the toggle joints are connected laterally of the actuating member 5. To this end, the latter carries the actuating pin 21 in the form of a pin extending through member 5. By means of another pin 24 extending through the pivoted part 8, the latter is mounted in two lugs 5a of the straining member 5. These lugs have been formed by milling or the like. It must be imagined that the entire mechanism is enclosed between the two side walls of the lighter housing which are connected by a non-illustrated top member.

It is apparent that the described invention will enable numerous modifications. For instance, a design would be possible which differs from that of FIGS. 1, 2 in that the spring member 6, 7 is arranged further upwardly at the position of the toggle joint 15, 16 whereas the toggle joint would be disposed further below. In that case, the spring 7 would have to be a tension spring which is tensioned by the rotation of the straining wheel rather than compressed, as before, so that the release of the cover lock causes the spring to pull the cover to its open position rather than to press it, as described hereinbefore.

A special advantage of the present system, which is protected from an unintended opening of the spring-loaded cover, is seen in that the rate at which the spring 7 is strained is without any significance for the speed at which the cover flies open, i.e., for the intensity of the resulting spark and for the force with which the cover 1 is held closed. The magnitude of the movement available for straining the spring may be relatively large and the spring may be slowly strained. This means that even where large forces are to be stored, such a lighter can be operated conveniently without special effort. Thus, the requirement has been fulfilled to provide a lighter which is actuatable even by persons who have only a small finger pressure.

I claim:

1. In a pyrophoric lighter, in combination,
- (a) a housing;
- (b) a cover member rotatable on said housing about an axis between an open and a closed position;
- (c) two elongated rod means constituting a toggle linkage, each rod means having a free longitudinal portion and another longitudinal portion hingedly connected to the other portion of the other rod means for pivotal movement of said free portions toward and away from a locking position;

- (d) fastening means pivotally securing said free portions to said cover member and to said housing respectively for holding said cover member in said closed position thereof when the free portions of said rod means are in said locking position;
- (e) holding means releasably holding said rod means in said locking position;
- (f) actuating means manually movable on said housing between an inoperative and an operative position;
- (g) resilient means operatively connected to said cover member for urging the same toward said open position thereof when said resilient means is stressed;
- (h) first motion transmitting means connected to said actuating means for stressing said resilient means during movement of said actuating means from said inoperative to said operative position thereof; and
- (i) second motion transmitting means connected to said actuating means for releasing said rod means from said locking position during said movement of said actuating means.

2. In a lighter as set forth in claim 1, said rod means in the locking position thereof being elongated substantially in a common direction.

3. In a lighter as set forth in claim 2, said rod means being secured to said cover member and to said housing by said fastening means for hinged movement of said free longitudinal portions toward each other when said cover member moves from the closed toward the open position.

4. In a lighter as set forth in claim 2, said second motion transmitting means being connected to said actuating means for releasing said rod means from said locking position after said resilient means is stressed by said first motion transmitting means.

5. In a lighter as set forth in claim 2, said actuating means being rotatably mounted on said housing, and spring means permanently urging said actuating means to move toward said inoperative position thereof.

6. In a lighter as set forth in claim 2, said holding means including stop means on said housing, and a spring member on said cover member urging one of said rod means against said stop means.

7. In a lighter as set forth in claim 1, means operatively connected to said cover member for striking a spark responsive to the movement of said cover member from the closed to the open position.
